INSULATED STRUCTURE

Luther E. Gaenzle, Lancaster, Pa., assignor to
 Armstrong Cork Company, Lancaster, Pa., a
 corporation of Pennsylvania

Application June 27, 1934, Serial No. 732,669

13 Claims. (Cl. 72-16)

This invention relates to thermally insulated structures of a type which can be assembled easily, disassembled without injuring any parts of the structure; and reassembled to form a structure which is as efficient as the original assembly. A structure of this type should be free from any cement coatings which crack under temperature variations and break in disassembly; the continuity of the insulation material should be maintained for efficiency; the insulation material should be protected from physical injury and the ingress of moisture; assembly and disassembly should be simple; and the finished structure should be light in weight and present a clean appearance.

In prior constructions, slabs of insulating material were secured in wood frames to form units and these units were assembled to form a structure. The wood frames broke the continuity of the insulation material and the insulating efficiency of the structure was reduced. The interior surfaces of these units were usually given a plaster coating. This coating frequently cracked under temperature variations and had to be broken if the structure were disassembled. These coatings allowed moisture laden air to filter into the insulation material where it condensed and further reduced the insulating efficiency. In constructions where a metal sheathing was provided, the sheathing was nailed to wood blocks and dowels inserted in the insulation material, and adjacent sheets of metal were welded together. Assembly of the latter structures was difficult and laborious. The insulation material had to be drilled and blocks (to which the sheathing was nailed) were glued in the holes. Extreme care had to be exercised in welding to avoid charing the insulation material. Furthermore, these structures could not be disassembled without destroying the sheathing and a great deal of the insulation material.

I have overcome the disadvantages of prior constructions by providing a light-weight structure of high insulating efficiency in which the insulation is protected against injury and the ingress of moisture and in which no plaster coats are necessary. My structure is easy to assemble, and can be readily disassembled without injuring any of the material; it presents a sanitary appearance and is easy to clean; and there is no means allowing through conduction of heat between the exterior and the interior of the structure.

My invention relates to insulated structures formed of sheathed panels of thermal insulation material, and I utilize the property of resiliency of the material or materials used in a structure to

obtain an effective seal between adjacent or complementary panels. The seal is effected and maintained by compressing the material or materials and utilizing the expansive force or thrust of such compressed material or materials. In a 5 preferred embodiment, the sheathed panels of insulation material are grooved at the portions thereof which lie adjacent or abut contiguous panels to form key ways or channels therebetween and key strips or splines are positioned in 10 the key ways. The key strips are preferably of thermal insulation material of the same general cross-sectional shape but slightly larger than the key ways so that when contiguous panels are drawn together, the key strips or the insulation 15 material, or both, will be compressed. A sealed joint is effected by the expansive force or thrust of the compressed material at the joint. Locking means are provided to lock adjacent panels together and to maintain the key strips in position. 20 When adjacent panels are positioned and before being drawn together, there are perceptible spaces or gaps between the same, so that in drawing such panels together substantial compression of 25 the key strips, or the insulation material, or both, is required to close these spaces.

In the accompanying drawings illustrating a present preferred embodiment of my invention,

Figure 1 is an isometric view, partly broken away, of a refrigerator cabinet embodying my 30 invention;

Figure 2 is a horizontal sectional view of the cabinet of Figure 1;

Figure 3 is an isometric view of a panel of the type I employ;

Figure 4 is a detail view of a joint between two adjoining panels;

Figure 5 is a sectional view to enlarged scale showing details of construction of the door sill and showing the door in closed position;

Figure 6 is a view on the line VI-VI of Figure 1; and

Figure 7 is a view similar to Figure 4, showing a modification.

Referring to Figure 1, the structure is made up 45 of panels P which comprise a core of insulation material 2 and metallic sheathing 3. I have shown both the insulation cores and the key strips as being made of cork. I prefer cork because it is light in weight, has thermal insulation 50 properties, is resilient and possesses some degree of structural strength. However, other materials may be used; and the key strips and panel cores may be of different materials if desired. The cores of insulation material are grooved, as 55

at 4, at the portions thereof which will lie adjacent or abut contiguous panels when assembled. It will be noted that a plane surface 5 is preferably allowed between the grooves and the edges 5 of the insulation core. This permits a better joint to be made between adjacent panels because there is a greater contacting surface area.

The protective sheathing 3 may be any light sheet metal, such as galvanized iron, stainless steel, or enamelled sheet metal. The sheathing is cut out at its edges to provide tabs 6. In forming the panels, the sheathing is bent over the plane surface 5 and the tabs are bent into contact with the inclined surfaces of the grooves. 10 In erection, key strips or splines 7 are positioned in the grooves and adjacent panels are drawn together. These key strips are preferably of the same cross-sectional shape as the key ways formed by the grooves in adjacent panels. I prefer to have both the insulation cores and the key strips made of resilient material, such as cork-board, so that a tight joint is formed between panels. However, if one material is rigid, a satisfactory joint can be formed if the other material is resilient. It is also possible to use rigid 15 materials for the insulation and the key strips by making the key strips smaller than, or the same size as, the key ways and providing them with a mastic coating which will flow when the panels are drawn together. Angles 8 are provided along the outer edges of the sheathed panels and are correspondingly positioned so that the panels may be drawn and locked together. Screws 9 are inserted in holes in the angles, and the panels 20 are drawn together and locked in position by drawing up the screws. If the angles 8 be objectionable from a decorative standpoint, they may be concealed by covering them with channel irons or the like, and thus a panel effect is imparted to 25 the structure.

In the modification shown in Figure 7, the insulation material 2 extends beyond the sheathing 3 at the edges; and tongues 31 are provided along the edges of the sheathing. In such a construction, the panels are urged together, substantially compressing the insulation material, and locking strips 32 are snapped or slid into engagement with oppositely disposed tongues on adjacent panels. The expansive force, or thrust, 30 of the compressed insulation material maintains the locking strip in position.

The floor panel P₁ rests on a reenforcing frame designated generally at 10. This frame extends around the edge of the floor panel, and angle 35 irons 11 (Figure 5) extend between frame members to provide support for the central area of the floor panel and to lend rigidity to the frame. Figure 5 shows the floor section at the door way. The front section of the frame 10 has angle irons 12 and 13 secured thereto. The angle iron 12 is tapped as at 14 and a breaker strip 15 is secured to the top of the frame by screws 16 (shown in dotted lines in Figure 5). This breaker strip prevents through conduction between the outer and 40 inner surfaces of the panels; and is stepped for reception of a correspondingly stepped door. The inner sheathing of the floor panel is lapped over and secured to the breaker strip at 17 and the outer (and lower) sheathing of the floor 45 panel is bent upward and inset into the breaker strip at 18. The remainder of the door jamb is similar in construction to the floor section. Referring to Figure 2, the panels P₆ and P₇ have re-enforcing members 19 adjacent the insulation material. The sheathing is extended about the

edges of these members at 20 and is held in place by angle irons 21 which are secured to the members 19 in the same manner that the angle irons 12 and 13 are secured to the floor frame. Breaker strips 22 are fastened to the angle irons 21. The door 23 is of conventional construction and, as shown, comprises a wood frame 24 which supports insulation material 25. A sheathing 26 is provided on its inner surface and a heavy gauge metal 27 is secured on the outer surface to 10 the frame 24. This heavy outer metal sheet reinforces the door and prevents it from deforming in use. The door is secured by hinges 28 to the reenforcing member 19 in the panel P₆. Gaskets 29 are secured to the door to prevent flow 15 of air between the door and breaker strip when the door is closed.

Referring to Figure 6, when a panel is grooved and no key strip can be used, the groove is filled with a plastic insulating material 30. This seals 20 the joints and fills the space between the angle irons 21, insuring that there will be no through conduction at these portions. Such construction is advantageously used above the door frame. 25

In erecting a structure according to my invention (Figures 1 and 2), the floor panel P₁ is put in position on the frame 10 and key strips are placed in the grooves in the upper face of the panel. Panel P₂ is set in position, a key strip is 30 set in the vertical groove in the face of the panel where it will abut panel P₃, and this latter panel is then positioned. The locking means are drawn up between panels P₁ and P₂, P₁ and P₃ and between P₂ and P₃; and a key strip is positioned in 35 the groove in the edge of P₃. Panel P₄ is then positioned and the locking means are tightened. A key strip is set in the vertical groove in P₂, and panel P₅ is placed and locked in position. Panel P₆ is set in place, and panel P₈ is put in place, 40 resting on the breaker strip on the top of the door jamb. Panel P₈ can then be locked in place. Key strips are placed in the vertical grooves in the edges of panels P₄ and P₆ and the end panel P₅ is set and locked in position. The structure is 45 completed by placing key strips in the upper edges of the wall panels and the top or ceiling panel P₉ is then put in place. When all the panels are locked, the structure is sturdy and the door can be hung. 50

In the interest of clearer illustration, shelving and supports for ice or mechanical refrigeration units have been omitted. However, I have shown reenforcing angle irons 33 which lend rigidity to the walls. 55

Since tight joints between adjacent panels are necessary to have an efficient structure, I may insert a plastic sealing compound or sealing gasket 34 (Figure 7) between the contacting surfaces of the sheathing of adjacent panels before or after the panels have been drawn together. I have found that an effective seal is formed by providing the key strip with a coating of asphalt or other sealing material 35 (Figure 4).

I have shown the key strip as being of the same 65 cross-sectional shape as the key way formed by contiguous panels, but they may be of any shape so long as they extend into contact with adjacent panels. It is desirable to have them of the same shape, however, since there is a greater area of 70 contact between the panels and key strips, and a more effective seal and better insulated joint are formed.

According to the present invention, the panels may be made up at the factory in standard sizes; 75

and relatively unskilled labor can be employed in erection. When the units of the structure are erected, the structure is finished. No waterproofing or plaster coats are necessary. This simplicity of erection is a big factor in reducing the cost since a high percentage of the cost of other types of structures is for skilled labor.

I have illustrated and described a present preferred embodiment of my invention. It will be understood, however, that it is not limited to the forms shown, but may be otherwise embodied within the scope of the following claims.

I claim:

1. An insulated structure comprising insulating panels grooved at the portions thereof adapted to contact contiguous panels to define channels therebetween, key strips disposed in said channels, and locking means securing contiguous panels together and sealing the joints therebetween by substantial compression of one of said materials.

2. An insulated structure comprising panels of insulating material grooved at portions thereof to define channels between contiguous panels, key strips of insulating material of a greater cross-sectional dimension than said channels disposed therein, and locking means securing contiguous panels together and sealing the joints therebetween by substantial compression of one of said materials.

3. An insulated structure comprising insulating panels grooved at portions thereof to define channels between contiguous panels, key strips of resilient insulating material of a larger cross-sectional dimension than said channels disposed therein and locking means holding the key strips in position in a substantially compressed state.

4. An insulated structure comprising panels formed of compressible insulating material having a protective sheathing secured thereto, said panels being grooved at portions thereof to define channels therebetween, compressible key strips disposed in said channels, and locking means engaging the sheathing of contiguous panels and holding said materials and key strips in a substantially compressed state.

5. An insulated structure comprising panels formed of insulating material having a protective sheathing secured thereto, said panels being grooved at portions thereof to define channels therebetween, key strips of insulating material of a greater cross-sectional dimension than said channels disposed therein, and locking means holding the sheathing of contiguous panels in abutting relation against substantial compression of one of said materials.

6. An insulated structure comprising panels formed of insulating material having a protective sheathing, said panels being grooved at portions thereof to define channels therebetween, key strips of resilient insulation material of a larger cross-sectional dimension than said channels disposed therein, and locking means holding the sheathing of contiguous panels in abutting relation by substantial compression of the key strip.

7. An insulated structure comprising panels formed of compressible insulating material having a protective sheathing, said panels having grooves in portions thereof to define channels therebetween, key strips of compressible insulating material of a larger cross-sectional dimension than said channels disposed therein, and locking means mounted on said sheathing holding contiguous panels in abutting relation by substantial compression of said materials.

8. An insulated structure comprising panels of insulating material having a protective sheathing, said panels being grooved at portions thereof to form channels therebetween, key strips of insulating material of the same cross-sectional shapes as and of a greater cross-sectional dimension than the channels disposed therein, and locking means mounted on said sheathing holding contiguous panels in abutting relation by substantial compression of one of said materials.

9. An insulated structure comprising sheathed panels of compressible insulating material having grooves in portions thereof to form channels therebetween, key strips disposed in said channels, locking means on said sheathing holding adjacent panels together in abutting relation with the said insulating material under substantial compression, and a plastic sealing compound disposed between the abutting portions of contiguous panels.

10. An insulating structure comprising a panel having a core of insulation material, metal sheathing covering one flat face and a portion only of one of the edges of the core, a similar sheathing covering the other flat face and covering said edge of the core over only a portion thereof spaced from the said edge portion covered by the first mentioned sheathing, a sheathed panel lying in contiguous relationship with respect to said edge of the first mentioned panel and having the edges of its sheathings disposed in spaced relationship, the arrangement being such that insulation material in the zone of the joint between contiguous panels is in substantially compressed condition, and locking means holding the abutting panels together against the tendency of the substantially compressed insulation material to expand, whereby the joint between the abutting panels is effectively sealed and through conduction avoided.

11. An insulating structure comprising a panel having a core of insulation material, sheathings covering the flat faces of the core in spaced relationship, a sheathed panel lying in contiguous relationship with respect to an edge of the first mentioned panel and having its sheathings disposed in spaced relationship, the arrangement being such that insulation material in the zone of the joint between contiguous panels is in substantially compressed condition, and locking means holding the abutting panels together against the tendency of the substantially compressed insulation material to expand, whereby the joint between abutting panels is effectively sealed and through conduction avoided.

12. An insulated structure comprising panels each having a core of insulation material with sheathings covering the flat faces thereof in spaced relationship, there being grooves formed in the contiguous edges of the insulation cores of adjacent panels, a nonconducting key strip disposed in the channel defined by contiguous grooves, the arrangement being such that the key strips are under substantial compression, and locking means holding the abutting panels together against the tendency of the substantially compressed insulation material to expand, whereby the joint between abutting panels is effectively sealed and through conduction avoided.

13. An insulating structure comprising a panel having a core of resilient insulation material, sheathings covering the flat surfaces of the core in spaced relationship, said insulation material normally extending beyond the sheathing when in the uncompressed state, a sheathed panel lying in contiguous relationship with respect to the

first mentioned panel and having its sheathings disposed in spaced relationship, the arrangement being such that the insulation material in the zone of the joint between contiguous panels is in substantially compressed condition, and locking means holding the abutting panels together

against the tendency of the substantially compressed insulation material to expand, whereby the joint between the abutting panels is effectively sealed and through conduction avoided.

LUTHER E. GAENZLE.
